DESIGN FOR A DISPLAY ALBUM

William Widder, New York, N. Y., assignor to J. Widder & Co., New York, N. Y., a copartnership comprised of Samuel Widder and William Widder

Application March 1, 1944, Serial No. 112,763

Term of patent 3½ years

(Cl. D61—1)

To all whom it may concern:

Be it known that I, William Widder, a citizen of the United States and a resident of Manhattan, in the county of New York, State of New York, have invented a new, original, and ornamental Design for a Display Album, of which the following is a specification, reference being had to the accompanying drawing, forming part thereof.

In which:

Figure 1 is a perspective elevational view of a display album embodying my design when closed.

Figure 2 is a perspective elevational view of a display album embodying my design when open.

I claim:

The ornamental design for a display album, as shown.

WILLIAM WIDDER,
